UNITED STATES PATENT OFFICE.

RUDOLPH C. RASMUSSEN, OF PHILADELPHIA, PENNSYLVANIA.

CLAMPING ATTACHMENT FOR NAILING-MACHINES.

1,392,222.

Specification of Letters Patent. Patented Sept. 27, 1921.

Application filed October 31, 1919. Serial No. 334,647.

To all whom it may concern:

Be it known that I, RUDOLPH C. RASMUSSEN, a citizen of the United States, residing at Philadelphia, in the county of Philadelphia and State of Pennsylvania, have invented new and useful Improvements in Clamping Attachments for Nailing-Machines, of which the following is a specification.

10 This invention relates to nailing machinery and it has more particular reference to machines for nailing boxes, crates and the like.

15 The main object of this invention is to provide a clamping attachment for automatically positioning and holding the parts to be nailed together in proper relation, said clamping attachment operating in advance of the nail drivers.

20 Another object of this invention is to provide a clamping attachment which can be quickly applied to existing nailing machines without the disconnection or displacement of any of the operative or other parts.

25 A still further object is to provide a clamping attachment which is simple to construct, cheap to manufacture and install, and which is not liable to get out of working order.

30 With these and other objects in view as will be later on more apparent my invention consists essentially in the novel features of construction, combination and arrangement of parts hereinafter fully described and 35 more specifically defined by the appended claim.

In the further disclosure of the invention reference is to be had to the accompanying sheet of explanatory drawings constituting 40 a part of this specification, and in which like characters of reference designate the same or corresponding parts in all the views, and in which:—

45 Figure 1—is a fragmentary front elevation of part of a box nailing machine showing my improved clamping device attached thereto.

50 Fig. 2—is an enlarged front elevation of the clamping attachment proper with parts broken away or in section to better disclose the underlying structure.

Fig. 3—is an end elevation looking to the right hand of the preceding figure.

55 Fig. 4—is a detail perspective view of the clamping member disconnected; and,

Fig. 5—is a fragmentary perspective

view of the clamping member operating element.

Referring to the drawings the numeral 10 designates part of the main frame of a box 60 nailing machine upon the front whereof is mounted or formed the box support or table 11. Transversely of the main frame are the customary cross bars 12, 12, on which are mounted the nail chucks 13, 13 connected 65 by chutes 14, 14, with the customary selectors 15, 15, the driving head being designated by the numeral 16, all of the foregoing mentioned parts being in accordance with the well known constructions and 70 which form no part of my present invention.

The clamping attachment proper comprises a rectangular housing or casing 17, closed in on its rear and forward faces by removable plates 18, 18 conveniently held in 75 place by screws 19, and this casing 17, is preferably securely clamped to the end of the frame supporting the cross bars 12, 12, by a Z-shaped strap or bracket 20, and screws 21, an adjustable leg or support 22, including upper and lower sections 23, 24 being provided beneath the casing 17. This adjustable leg or support 22, serves in use to stabilize the attachment and also to make provision for always supporting the same 85 directly upon the table 11, when the latter is raised or lowered to accommodate different depths of boxes and to this end the upper and lower sections 23, 24, are slotted at 25, to receive bolts 26, whereby said parts 90 are rigidly clamped together in adjusted relation.

Slidably mounted in the aforesaid housing 17 is a block 27 provided at one of its upper sides with an inclined part 28 with 95 which is adapted to coöperate a similarly inclined end 29, of a plunger member 30, provided with an upwardly extending portion or rod 31, adapted for adjustable connection by means of lock nuts 32, to the nail 100 driving head 16. It is to be here noted that the plunger member 30 is shown as rectangular in cross section and that it operates through a correspondingly shaped aperture 33, in the crown of the housing 17, but it 105 will be readily understood that any other appropriate section may be employed provided it is arranged to have an axial movement longitudinally only.

Projecting laterally from the aforesaid 110 block 27, is a rod 34, provided at its outer end with a head 35, and said rod 34, and

block 27 are normally projected to the right hand in Fig. 2, by a compression spring 36, the latter in turn being housed in a recess 37, about the inner end of the rod; and said 5 spring abutting against the side wall of the casing 17, a hole 38, being provided for the passage of the rod 34 through the side wall.

In some instances I may employ a steady- 10 ing bearing or hanger guide 39, adapted for fixture where desired on the aforesaid cross bars 12, 12 by a screw 40, but in most instances I find this bearing or guide unnec- 15 essary.

In use and assuming that a box 41,—Fig. 15 1,—has been placed upon the table 11 to have the bottom or top 42, nailed there- to said box is placed against the guide 43 and moved rearwardly to the requisite position with the top or bottom to be nailed 20 thereon, whereupon the operator trips the machine in the well known way, which causes the driving head 16, to commence to descend, which in turn through the connected rod 31, projects the block 27, toward 25 the left hand in Fig. 2. This movement of the block 27 moves the head 35, against the right hand edge of the box bottom or top 42 in advance of the nailing operation and insures said bottom or top being properly 30 aligned relative to the sides or ends of the box prior to the actual nailing. On the re- turn of the driving head 16, to its normal position the spring 36 returns the block 27 to its normal or out of the way position.

While I have shown and described one 35 practical and the preferred embodiment of my invention I wish it clearly understood that slight changes may be made in the form, disposition and combination of the several parts to accommodate my invention to different types of nailing machines, and it is desired to protect all such changes and other arrangements as may reasonably be construed as falling within the scope of 40 the appended claim. 45

Having described my invention, what I claim as new and desire to secure by Letters Patent, is:—

A clamping attachment for nailing machines comprising a rectangular casing 50 equipped for attachment to a stationary part of the machine, a slidable block in said housing and having an inclined face, said slidable block having an element extending through a wall of the casing and being 55 adapted for movement in opposition to compression means for clamping the part to be nailed in proper position, the said compression means interposed between the block and said wall of the casing and a de- 60 pending plunger adapted to be attached to and carried by the driving head and having an inclined portion at its lower part for co- 65 operation with the aforesaid inclined face of the movable member to actuate the latter in advance of an actual nailing operation.

In testimony whereof I affix my signature.
RUDOLPH C. RASMUSSEN.
